UNITED STATES PATENT OFFICE.

ALBERT J. THROM, OF GRAPEVILLE, PENNSYLVANIA.

FOUNT CUT.

Application filed June 23, 1925. Serial No. 39,078.

To all whom it may concern:

Be it known that ALBERT J. THROM, a citizen of the United States of America, residing at Grapeville, in the county of Westmoreland and State of Pennsylvania, has invented new and useful Improvements in Fount Cuts, of which the following is a specification.

The object of the invention is to provide a glass mold particularly adapted for the production of small glass castings, such as door knobs, drawer knobs and the like; to provide a shearing means for cutting the surplus or excess glass from the cast article in order that the usual finishing may be reduced to a minimum or dispensed with entirely; and to provide a plunger for forcing the molten glass into the mold and compressing receding elements operable by the surplus glass to make room for the latter.

With this object in view, the invention consists in a construction and combination of parts of which a preferred embodiment is illustrated in the accompanying drawings, wherein:

Figure 1 is a central longitudinal sectional view through the improved mold.

Figure 2 is a horizontal longitudinal sectional view on the plane indicated by the line 2—2 of Figure 1.

Figure 3 is a transverse vertical sectional view on the plane indicated by the line 3—3 of Figure 1.

Figure 4 is a top plan view.

The mold comprises the base member 10 and the complementary side members 11 and 12, the latter being hingedly connected with the base member by means of the intercurrent eyes 13 which engage a pin 14 upstanding from and set in the base member 10. Thus the side members may be swung laterally away from the bottom member 15 which is detachably secured to the base as by a transversely dovetailed shaped tongue and groove connection consisting of the tongue 16 of the base which engages a corresponding groove in the member 15.

When the side members are swung into abutting engagement with the bottom member 15, the mold is in condition for the casting operation and the side members are interlocked by a pin 17 engaging intercurrent eyes 18 in the mold members, this pin being provided with a right angularly disposed tang 19 for the detachable reception

of a handle to permit the ready withdrawal and insertion of the pin.

To provide for swinging the side members of the mold, the latter are provided with integral shanks 20 threaded, as at 21, for the detachable reception of handles to permit of their ready movement.

Complementary to the bottom member 15 is a detachable shell 22 supported on pins 23 carried by the base member 10 and this shell together with the bottom member 15 and complementary cavities 24 in the side members, defines the shape of the articles to be cast, for example, the door knob or drawer knob 25 illustrated in Figure 1.

Above the shell, the side members are hollowed out, as indicated at 26, to provide a fount for the molten glass, this fount being bounded by a peripheral flange 27 defining an opening adapted for the reception of the plunger 28. Thus, below the flange, a recess is provided throughout the perimeter of the fount for excess or surplus glass.

As the molten glass is poured into the fount, the plunger at this time being withdrawn or removed, it flows through the openings 30 in the shell and into the cavities 24. Thereafter by the insertion of the plunger, the latter being carried by the chuck in the conventional press, the glass is compacted into the cavities as the plunger descends until finally the bosses 29 on the lower end of the plunger, and shaped to conform to the mouths or openings 30 in the shell, enter the latter and shear off or separate the surplus glass from the molded article 25, the surplus glass flowing into the space bounding the plunger below the flange 27.

This space is not sufficient, however, to care for all the surplus glass resulting from supplying sufficient to fully compact the same into the molded article and the plunger is, therefore, provided with receding elements 31 constituting side plates disposed on opposite sides of the plunger and interconnected by a transverse yoke piece 32 slidably engaging an opening 33 in the plunger and actuated by a compression spring 34, this spring tending to normally force the yoke on the bottom of the opening 33 and thus yieldingly hold the receding elements with their bottom edges flush with the bottom face of the plunger. The recession of the members 31, due to the pressure of the

excess glass, provides additional space for such excess and permits the ready entrance of the bosses 29 into the openings 30.

When knobs are cast with the faces uppermost and the fitters downward, the bottom member 15 is provided with raised ribs 35, or raised portions of other contour, to give the fitter the desired decorative appearance; or, if the fitter is of socket form, the elements 35 may be in the form of a plunger with the decorative design on the upper face. Obviously, the knobs may be cast in positions the opposite of that shown, in which case the bottom member 15 will have simply 10 a plain top face and the plunger will have bosses to socket and decorate the fitter.

The shell 22 is removable, when the side members of the mold are swung to open position, by means of a tang 36 adapted for the 20 reception of a detachable handle.

The invention having been described, what is claimed as new and useful is:

1. A mold for the purpose indicated comprising a base and movable side members secured to the base, a shell supported by the base and enclosed by the side members, and a plunger insertible in a space defined by the side members when in closed position, the plunger at its lower end engaging the shell and the latter and the side members below the shell defining the shape of the articles to be cast.

2. A mold for the purpose indicated comprising a base and movable side members secured to the base, a shell supported by the base and enclosed by the side members, and a plunger insertible in a space defined by the side members when in closed position, the plunger at its lower end engaging the shell and the latter and the side members below the shell defining the shape of the articles to be cast, the plunger having a boss on its lower face entering an opening in the shell to shear the surplus glass from the cast articles.

3. A mold for the purpose indicated comprising a base and movable side members secured to the base, a shell supported by the base and enclosed by the side members, the latter and the shell defining the shape of articles to be cast and the side members above the shell being hollowed out to provide a fount, and a plunger insertible in the fount and having shell engaging means to shear the surplus glass from the cast article.

4. A mold for the purpose indicated comprising a base and movable side members secured to the base, a shell supported by the base and enclosed by the side members, the latter and the shell defining the shape of articles to be cast and the side members above the shell being hollowed out to provide a fount, a plunger insertible in the fount and having shell engaging means to shear the surplus glass from the cast article,

and receding members actuatable by the surplus glass to provide space for the latter around the plunger.

5. A mold for the purpose indicated comprising a base and movable side members secured to the base, a shell supported by the base and enclosed by the side members, the latter and the shell defining the shape of articles to be cast and the side members above the shell being hollowed out to provide a fount, a plunger insertible in the fount and having shell engaging means to shear the surplus glass from the cast article, and receding members actuatable by the surplus glass to provide space for the latter around the plunger, said receding members consisting of sliding plates mounted on opposite sides of the plunger and yieldingly impelled toward the shell engaging end of the latter.

6. A mold for the purpose indicated comprising a base and movable side members secured to the base, a shell supported by the base and enclosed by the side members, the latter and the shell defining the shape of articles to be cast and the side members above the shell being hollowed out to provide a fount, a plunger insertible in the fount and having shell engaging means to shear the surplus glass from the cast article, and receding members actuatable by the surplus glass to provide space for the latter around the plunger, said receding members consisting of sliding plates mounted on opposite sides of the plunger, a yoke disposed transversely of the plunger and traversing a slot in the latter and connected with the side plates, and a compression spring housed in the slot and bearing upon the yoke.

7. A mold for the purpose indicated comprising a base, side members having intercurrent eyes hingedly engaging a pin upstanding from the base, a bottom member mounted upon the base between the side members, a locking pin engaging intercurrent eyes in the side members when the latter are in abutting relation with said bottom member, a shell detachably supported by the base, said shell having openings and the side members being hollowed out and they and the shell defining the shape of an article to be cast, the side members being hollowed out above the shell to provide a fount for the reception of molten glass, and a plunger insertible in the fount to compress the glass into the article receiving space in the side members and the shell.

8. A mold for the purpose indicated comprising a base, side members having intercurrent eyes hingedly engaging a pin upstanding from the base, a bottom member mounted upon the base between the side members, a locking pin engaging intercurrent eyes in the side members when the latter are in abutting relation with said bottom member, a shell detachably supported by the

base, said shell having openings and the side members being hollowed out and they and the shell defining the shape of an article to be cast, the side members being hollowed out 5 above the shell to provide a fount for the reception of molten glass, and a plunger insertible in the fount to compress the glass into the article receiving space in the side members and the shell, the plunger being 10 provided with means for shearing the surplus glass from the cast article at the opening of the shell.

9. A mold for the purpose indicated comprising a base, side members having intercurrent eyes hingedly engaging a pin up-standing from the base, a bottom member mounted upon the base between the side members, a locking pin engaging intercurrent eyes in the side members when the lat-

ter are in abutting relation with said bottom member, a shell detachably supported by the base, said shell having openings and the side members being hollowed out and they and the shell defining the shape of an article to be cast, the side members being hollowed 20 out above the shell to provide a fount for the reception of molten glass, and a plunger insertible in the fount to compress the glass into the article receiving space in the side members and the shell, the plunger being 25 provided with means for shearing the surplus glass from the cast article at the opening of the shell, and provided with yieldable 30 receding elements to provide space for the surplus glass around the plunger. 35

In testimony whereof he affixes his signature.

ALBERT J. THROM.
